Fosgood Corporation, Leominster, Mass., a corporation of Massachusetts

Application June 21, 1947, Serial No. 139,855

Term of patent 7 years

(Cl. D44—24)

To all whom it may concern:

Be it known that I, Bernard Ulvad, a citizen of the United States, residing at Leominster, in the county of Worcester, State of Massachusetts, have invented a new, original, and ornamental Design for a Napkin Holder or the like, of which the following is a specification, reference being had to the accompanying drawings, forming part thereof, in which:

Figure 1 is a front view of a napkin holder or the like embodying the design;

Fig. 2 is an end view thereof; and,

Fig. 3 is a sectional view taken on the line 3—3 of Fig. 1.

I claim:

The ornamental design for a napkin holder or the like, substantially as shown.

BERNARD ULVAD.
